GARMENT HANGER

Benjamin Belefant and Hussein Hassan,
New York, N. Y.

Application February 26, 1935, Serial No. 8,243

5 Claims. (Cl. 223—91)

This invention relates to improvements in garment hangers and more particularly to a combined coat and trousers hanger.

One of the main objects of the invention resides in a garment hanger in which the trousers support may be swung to a position beyond a coat supported upon the hanger to facilitate the easy removal or replacement of a trousers without disturbing the coat in its hung position upon

10 the hanger.

Another feature of the invention is to provide a coat and trousers hanger by which the trousers may be gripped in a hung position to prevent accidental slipping of the same from the hanger, the trousers hanger section being pivoted to the coat hanger section, and held in clamping position and against accidental swinging movement by a releasable catch means between the coat hanger section and the trousers hanger section.

20 A further feature is the provision of a garment hanger having the above advantages which is simple and inexpensive of construction, and strong and durable to withstand the shocks to which such an article is subjected during general use.

With these and other objects in view, the invention resides in the certain novel construction, combination and arrangement of parts, the essential features of which are hereinafter fully described, are particularly pointed out in the appended claims, and are illustrated in the accompanying drawing, and in which:

35 Figure 1 is a perspective view of the improved garment hanger in use with a coat supported upon the coat hanger section and the trousers hanger section extended with a trousers supported thereon.

40 Figure 2 is a side elevational view with the coat removed and the trousers section in gripping and locked position.

Figure 3 is a top plan view of the garment hanger per se with the trousers section extended.

45 Figure 4 is an enlarged fragmentary vertical sectional view on the line 4—4 of Figure 3 with the trousers section in locked position.

Figure 5 is a detail horizontal sectional view on the line 5—5 of Figure 4.

50 Figure 6 is a detail horizontal sectional view on the line 6—6 of Figure 4.

Figure 7 is a perspective view of a modified form of the invention.

55 Referring to the drawing by reference characters, the numeral 10 designates the improved

garment hanger in its entirety, and which includes a substantially inverted V-shaped coat hanger section 11. The coat hanger section 11 comprises a pair of outwardly diverging arms 12 and 13 joined together by a tenon joint 14 at their apex or meeting ends. The free end of the arm 12 is provided with an inwardly extending portion or enlargement 15 which may be formed integral with the said arm or a separate piece rigidly joined thereto. The lower end of the arm 13 terminates in a flat face 16 short of the plane of the free end of the arm 12 and pivotally supports a trousers hanger section designated in its entirety by the numeral 17. The hanger includes the usual hook 18 rising from the apex portion of the coat hanger section by which the device may be hung upon a rod, hook or other supporting element. The hook 18 is preferably swivelly connected to the hanger to enable turning of the same relative thereto.

The trousers hanger section 17 includes a pair of coacting clamping bars 19 and 20. One end of the bar 19 is pivoted to the flat face 16 of the arm 13 as at 21 whereas the other end of the same and one end of the bar 20 are pivotally connected as at 22. The inwardly facing sides of the bars 19 and 20 are cut away as at 23 and 24 respectively to provide spaced portions or jaws between which the legs of a trousers pass and are held by the gripping action therebetween. The inner faces of the cut away portions are lined with felt or other like soft friction material 25.

The pivoted end of the bar 20 clears the inwardly extending portion 15 but the adjacent end of the bar 19 extends beyond the end of the bar 20 and terminates in a beveled face 26 for abutting engagement with a similar beveled face 27 provided on the vertical wall of a horizontally disposed recess 28 provided in the extension portion 15. The beveled end of the bar 19 is provided with a keeper recess 29 for receiving a latch bolt 30 slidably mounted in a recess 31 in the portion 15. A spring 32 is interposed between the inner end of the latch bolt and the end wall of the recess 31 to normally urge the latch bolt outwardly, and which outwardly extending movement is limited by engagement of a manipulating pin 33 engaging one end of a slot 34 in the portion 15. The pin 33 extends downwardly below the lower edge of the portion 15 and it is by the manipulation of the pin that the latch bolt may be manually moved to a retracted position free of the keeper 55

recess 29. The outer end of the latch bolt is beveled as at 35 to snap into the keeper recess when the trousers hanger is swung to a closed position.

5 The free end of the lower bar 20 is beveled as at 36 for abutting engagement with a similar beveled face 37 provided on the bar 19. The coacting beveled faces 36 and 37 serve to limit the swinging movement of the bar 20 to closed or clamping position and support the free end of the bar 20 with its load, thus relieving the strain upon the pivot 22.

10 By reference to Figure 1 of the drawing, it will be seen that with a coat A hung upon the coat hanger 11, there is no interference with the opening of the trousers hanger as the same may be swung to an extended position through the open front of the coat and clear of the same. In order to swing the trousers hanger to extended position, it is only necessary for an operator to grasp the manipulating pin 33 and move the same toward the left, thus releasing the bolt 30 from the keeper recess 29. The bars 19 and 20 are now free to swing forwardly as a unit 15 upon the pivot 21 and when swung clear of the coat A, the bar 20 may be swung rearwardly in extended relation with respect to the bar 19 as shown in Figure 1. When in this position, a trousers B may be hung upon the bar 20 or 20 removed therefrom without in any way distributing the coat A in its hung position upon the hanger 11. In the event that the trousers B are being placed upon the arm 20 for hanging, the arm 20 is swung rearwardly to closed position in alinement with the bar 19 and the two bars swung as a unit to their final position bridging the free ends of the arms 12 and 13 of the coat hanger section 11, and in which position the bar 19 is locked against swinging movement by reason of the bolt 30 entering the keeper recess 29. When the two bars 19 and 20 are swung to a closed position, they grip the trousers therebetween and hold the trousers against accidental slipping.

15 In Figure 7 there is shown a slight modification of the means for securing the trousers hanger section in closed position. In this form, the inwardly extending portion 15' is provided with a keeper recess 38 which opens onto the front of the portion 15' through a restricted entrance or mouth 39, the lower wall of which is beveled in a forward direction as at 40 to cause the pin 41 extending from the bar 19 to ride into the keeper recess when the trousers hanger is swung to a closed position. To swing the trousers hanger to open position, the pin 41 must be lifted from the bottom of the keeper recess 38 where it is seated, and which vertical movement is slight and facilitated by the play in the pivotal connection of the trousers hanger with the coat hanger section. This lifting of the pin is necessary so that the same may pass through the restricted entrance 39. This catch means is the equivalent to the spring actuated bolt 30 and keeper recess 29 shown and described in the preceding form of the invention. The garment hanger herein set forth will not only be found convenient for home use, but will also be useful in clothing establishments wherein stock clothing may be hung on racks for display and try on purposes by prospective purchasers. The novel

trousers hanger section in association with the coat hanger section facilitates the display of the trousers without removing the coat or trousers from their hung position.

5 While we have shown and described what we consider to be the most practical embodiments of our invention, we wish it to be understood that such changes as come within the scope of the appended claims may be resorted to if desired.

10 Having thus described the invention, what we claim as new and desire to secure by Letters Patent is:

1. A garment hanger comprising a coat hanger section having outwardly diverging arms, a 15 trousers hanger section pivoted to the outer end of one of said arms, said trousers hanger section including a pair of pivotally connected bars between which a pair of trousers are adapted to be supported, and catch means between one of said 20 bars and the outer end of the other of said arms for securing said trousers hanger section in closed position.

2. A garment hanger comprising a coat hanger section of substantially V-shape, a trousers hanger section including a pair of pivotally connected bars between which a pair of trousers are adapted to be supported, one of said bars being pivotally connected to one of the free ends of said hanger section, the other of said bars being swingable 30 to an open extended position beyond one end of the other bar and to a closed position thereunder, and releasable catch means for securing the trousers hanger section against swinging movement in a closed position across the free ends of 35 the coat hanger section.

3. A garment hanger comprising a coat hanger section having outwardly diverging arms, a trousers hanger including an upper bar pivoted to the free end of one of said arms and adapted 40 to swing to a closed position to bridge said arms, a lower bar pivoted to the free end of said upper bar for swinging movement to a position in vertical alinement therewith or to an extended 45 position beyond one end thereof, stop means for limiting the closing movement of said lower bar, and releasable catch means for securing the trousers hanger section in closed position.

4. A garment hanger comprising a coat hanger section having outwardly diverging arms, a 50 trousers hanger section pivoted to the outer end of one of said arms and having a keeper recess in the free end thereof, and a releasable spring actuated latch bolt mounted in the outer end of the other of said arms for reception in said keeper 55 recess when said trousers hanger section is in closed position.

5. A garment hanger comprising a coat hanger section having outwardly diverging arms, a trousers hanger section pivoted to the outer end of 60 one of said arms and swingable to a closed position between said arms, the outer end of the other of said arms having a keeper recess therein provided with a restricted entrance, and a pin extending from the free end of said trousers hanger 65 section for passage through said restricted entrance and for seating in said recess when the trousers hanger is in closed position.

BENJAMIN BELEFANT.
